(57) **CLAIM**

The ornamental design for a display screen with a graphical user interface for medical software, as shown and described.

DESCRIPTION

FIG. 1 is a front view of a display screen with a graphical user interface for medical software, showing a first embodiment of the new design;

FIG. 2 is a second embodiment thereof;

FIG. 3 is a third embodiment thereof;

FIG. 4 is a fourth embodiment thereof; and,

FIG. 5 is a fifth embodiment thereof.

The broken line immediately adjacent to the outer edge perimeter of the graphical user interface shows a display screen, and forms no part of the claimed design. All other broken lines showing portions of the graphical user interface depict portions of the article and form no part of the claimed design.
